UNITED STATES PATENT OFFICE.

HERMAN F. SCHRAGE, OF PALATINE, ILLINOIS.

FOLDING CAR-STEP.

1,135,141.

Specification of Letters Patent. Patented Apr. 13, 1915.

Application filed December 24, 1914. Serial No. 878,912.

To all whom it may concern:

Be it known that I, HERMAN F. SCHRAGE, a citizen of the United States, residing at Palatine, in the county of Cook and State of Illinois, have invented certain new and useful Improvements in Folding Car-Steps, of which the following is a specification.

This invention relates to improvements in folding car steps for railway cars, and has for its object to produce an auxiliary step of this class hinged to the lower end of a stepway of a car platform and connected to and operated by a trap door which normally closes the upper end of the stepway and which is hinged to the door of the vestibule of the car.

The invention is simple in construction, positive and efficient in operation.

With the foregoing and other objects in view the invention consists in the combination and arrangement of parts to be herein-after fully described in the following specification, pointed out in the claims and illustrated in the accompanying drawings which form a part of said specification and in which—

Figure 1 is an end view of a vestibuled railway car with the platform and stepway in section and provided with my improved folding step. Fig. 2 is a similar view with the vestibule door open. Fig. 3 is a side view of Fig. 2. Fig. 4 is a plan view of the rod socket employed. Fig. 5 is a fragmentary view of the rod showing its enlarged end. Fig. 6 is a side elevation, of one section of the socket shown in Fig. 4. Fig. 7 is a front view of Fig. 6. Fig. 8 is a view of the opposite end of the rod of Fig. 5 and its connections. Fig. 9 is a plan view of Fig. 8. Fig. 10 is an end view of the auxiliary step. Fig. 11 is a section taken on line 11—11 of Fig. 10. Fig. 12 is an enlarged fragmentary portion of the slotted trap door and connections. Fig. 13 is a vertical section through Fig. 12.

Like reference characters indicate corresponding parts throughout the several views.

The reference numeral 1 designates the end wall of a vestibuled railway car, 2 the platform, 3 the stepway and 4 the door of the vestibule. To the door 4 a trap door 5 slotted longitudinally at 5^a is hinged as at 6 so that it may be moved through an arc of approximately 90 degrees when the door 4 is closed and when the trap door is in closed position it closes the upper end of the step-

way. The trap door is provided with a hand ring 7 by means of which it may be moved. A 2-piece plate 8 is fastened to a T-block 8^a that rides in the slotted portion 5^a of trap door 5 and the same carries a 2-piece bearing 9 which serves as a cup for the enlarged end 10 of a pitman 11, the cup and end 10 forming a ball and socket joint. The opposite end of the pitman 11 is fastened by means of a clamp 12 to a 2-piece socket 13 adapted to releasably retain the enlarged end 14 of a gooseneck lever 15 which is pivotally hung at 16 in a bearing 17 secured to a riser and one of the steps of the stepway; the other end of said gooseneck lever pivotally carries a pitman 18 which terminally carries a pivot 19 that is slidably disposed in the cam-recessed portion 20, 20^b of auxiliary step 21, said step being hinged at 22 to the lower end of the stepway. A plate 21^a secured as at 21^b to the auxiliary step is slotted at 20^c and formed with a shoulder 20^d. The recess 20 is slightly curved while the recess 20^b is greatly curved. To the plate 21^a a spring 23 is secured as at 24 and said spring passes between guide pins 25 and extends as at 26, 27 across the central channel 20^c near one end of the same. Another spring 28 secured to plate 21^a at 29 passes between guide pins 30 and extends across the channel 20^c near its opposite end.

Operation:—In Fig. 1 of the drawings the full lines show the step and connections in closed or inoperative position. The vestibule door is closed and the trap door down. To throw the step into operative position (shown in dotted lines) the trap door is raised by the hand ring 7 until it stands against the back of the door 4 and this operation will move the gooseneck lever into the position shown in dotted lines and the pitman 18 will press the pin 19 against the slotted portion of the plate 21^a but the pin 19 coming in contact with the spring 28 will not be permitted to pass through the portion 20 but will be deflected into the slotted portion 20^b and as it rides through this portion and through the portion 20^c forces the step into operative position or into position shown in dotted lines in Fig. 1 of the drawings. The door 4 can now be opened and the auxiliary step will be retained firmly in operative position. When the door 4 is closed again and the trap door lowered the lever 18 will pull upon the pivot 19 which must travel back to its original position

through the channeled portion 20, as contact with spring 23 will not permit it to do otherwise, thus moving the step 21 back upon its hinge 22 into inoperative position.

5. What is claimed is:

1. The combination with the stepway and door of a vestibuled railway coach, of a trap door hinged to said door and adapted when closed to close said stepway, an auxiliary step hinged to the lower step of said stepway and connection between said door, stepway and auxiliary step whereby movement of said door will operate to move said auxiliary step and to position it operatively as 10.
15. said door is opened.
2. The combination with the stepway and door of a vestibuled railway coach, of a trap door hinged to said door and adapted when closed to close said stepway, a pitman connected to said door, a goose neck lever swiveled to said pitman and pivotally connected to said stepway, another pitman pivotally connected to said gooseneck lever, an auxiliary step hinged to the last step in 20 said stepway, a slotted plate secured to said auxiliary step and a pivot carried by said last named pitman and disposed in the slotted portion of said plate whereby the 25

same may be moved into and out of operative position.

3. The combination with the stepway and door of a vestibuled railway coach, of a trap door hinged to said door and adapted when closed to close said stepway, a pitman connected to said door, a gooseneck lever 25 swiveled to said pitman and pivotally connected to said stepway, another pitman pivotally connected to said gooseneck lever, an auxiliary step hinged to the last step in said stepway, a plate formed with a slightly 40 curved slot and with a greatly curved slot merging into the first named slot, a pivot carried by said last named pitman and disposed in the slotted portion of said plate and springs secured to said plate and extending across one end of each of said slots to deflect said pivot into the opposite slot.

In testimony that I claim the foregoing as my own I have hereto affixed my signature in the presence of two subscribing witnesses.

HERMAN F. SCHRAGE.
